UNITED STATES PATENT OFFICE

CHARLES G. RICHARDSON, OF SPRINGFIELD, VERMONT, ASSIGNOR TO PARKS & WOOLSON MACHINE COMPANY, OF SPRINGFIELD, VERMONT, A CORPORATION OF VERMONT

EDGE SHEARING DEVICE

Application filed March 4, 1931. Serial No. 520,012.

This invention relates to devices for shearing the threads that project from the side edges or selvage of woven cloth such as may be left after the loop threads, formed at the selvage in an automatic pattern loom, are cut or that may be formed as a result of other modes of weaving. The shearing or cutting off of these threads projecting weftwise from the cloth is attended with considerable difficulty because of the danger of cutting the edge of the cloth itself, as it swerves in and out on either side, and for that reason this edge shearing is usually done by hand.

The present invention is intended to provide a simple edge shearing device constructed and arranged to insure the shearing of all the projecting threads, while at the same time protecting the cloth edge from injury by the cutter.

In a general way the invention comprises a fly blade or cutter mounted to rotate about a vertical axis in association with a relatively fixed tangential blade combined with a cloth protecting guide, which prevents the cloth from swerving against the cutting knives while means are employed for directing or moving the threads outwardly away from the edge of the cloth into the path of the cutter.

Another feature of the invention consists in the provision of means controlled by the cloth for automatically shifting the edge protecting guide and the shear blades with the cloth as the cloth edge swerves in and out, so that the shearing line of the shearing couple is always maintained close to the adjacent edge of the cloth travelling by as the cloth swerves in or out.

These and other features of the invention will be particularly described in the following specification and will be defined in the claims hereto annexed.

In the accompanying drawings I have illustrated a simple and effective construction and arrangement embodying the principles of this invention. The device may be constructed as an attachment for a face shearing machine having opposed units arranged on the right and on the left sides of the cloth and usually located in the machine

to shear the projecting threads after the cloth has passed by a loop cutting device which severs the edge loops formed in pattern weaving.

In the drawings

55

Fig. 1 represents a plan view of a machine to opposite sides of which my shearing attachment or device is applied.

Fig. 2 is an enlarged plan view of the shearing device on the right hand side of the machine, parts being removed or broken away to better show details of construction.

Fig. 3 is a side elevation of the construction shown in Fig. 2, parts being sectioned or broken away to better illustrate details.

65

Fig. 4 is a detail view in vertical cross section showing the protective guide embracing the edge of the cloth adjacent to the shearing couple.

Fig. 5 is a rear elevation, partly in section, illustrating the principal parts of the shearing mechanism shown in Figs. 1 and 2.

Fig. 6 and Fig. 7 are detail views showing in rear elevation and in plan, respectively, the shearing cutter in association with the protective cloth guide.

75

Fig. 8 is a rear elevation with parts broken away and sectioned showing the automatic feeler and adjusting mechanism by which the shearing couple and the protective guide are caused to follow the lateral swerving movements of the cloth.

Fig. 9 is a detail view of the pivotal dog which acts as a feeler to shift the shear carriage in and out through contact with the edge of the cloth.

The frame work A of the machine, to which the device is applied, may be of any suitable construction to support the various parts of the machine including the edge shearing attachment. In said frame is mounted a horizontal table 1 over which the cloth travels rearwardly, said table being cut on either side, as shown at 1^a, to form a space for the inward movement of the shearing and associated parts, as well as to allow the inward adjustment of those parts to accommodate narrower widths of cloth. Fixed to the frame a is a transverse bracket or beam 2 of U-shape in cross section, whose vertical

90

95

100

sides are provided with a pair of upper anti-friction bearing rolls 3 and a pair of lower anti-friction bearing rolls 4 between which are slidably supported the slide bars 5 of a carriage formed by these slide bars and an outer tie bar 5^a, thus making a rectangular frame slidable transversely of the cloth on which are mounted the shearing couple and the protective guides.

10 Intermediate of its ends this carriage is provided with a cross bar 6 to which is secured a downwardly depending angular bracket 6^a, whose lower offset end is provided with a vertical slideway forming a bearing guide for a vertical slide bar 7, which is provided at its lower end with a foot 7^a in which is mounted a bearing ball 7^b resting upon, and supported by, an eccentric cam 8 secured to a rotary shaft 8^a, said cam having sufficient axial length to support the bearing ball as the carriage which carries the slide moves in and out to follow the lateral swerving of the cloth. A top bearing 9 serves to steady the vertical slide bar and it will be understood that this slide bar forms the support for the shearing couple, the object being to reciprocate or traverse the rotary cutter vertically across the line of the cloth, so that substantially the whole width, or more 20 properly the vertical height of the cutting edges, may be utilized to distribute wear on the cutter.

25 The shearing couple comprises a rotary fly blade, that is, a cutter provided with peripheral helical blades, secured to a vertical driving shaft 14 and a relatively fixed tangential blade 12^a, which is carried by a supporting plate or block 12 which is adjustably secured to the vertical slide or carrier 7 to bring the 30 cutting edge in correct tangential relation to the periphery of the rotary fly blade. This adjustment is effected by an adjusting screw 12^b passing through an angle lug of the plate block 12 and engaging the carrier slide 7.

45 The fly blade itself is made adjustable in and out, or toward and away from the cutting edge of the blade 12^a, so that by the right angle adjustment of the two members of the shearing couple proper coordination 50 thereof and adjustment in relation to the protective guard, later to be described, may be secured.

55 The fly blade shaft 14 extends down through a bearing head 15 provided with a horizontal slide 16 having a horizontal dovetail sliding engagement with a supporting bracket 17, that is securely fastened also to the vertically movable carrier slide 7.

60 A lubricating strip 18 of leather and oiled felt is attached to the bearing head of the rotary fly blade to lie in light contact therewith, which serves to clear the blade of lint, keep its edges smooth and provide a slight lubrication of the edges of the individual

blades before they pass by the tangential cutter blade 12^a.

Above the cross bar 6, which forms the support for the slide-carrying bracket 6^a, is mounted a cross piece or bridge 10, whose downwardly projecting legs 10^a are secured to the inside of the carriage members 5. On this horizontal bridge or bracket 10 is secured the lower or base member 20 of a sheet metal guide, which at its outer end is formed with an upstanding flange 20^a which forms an exterior stop limiting the outward movement of the cloth passing over its horizontal member. Adjustably secured in spaced relation to the lower protective cloth guide is 70 the upper cloth guide member 21, which also has an upstanding vertical flange 21^a which is bolted to the corresponding flange 20^a of the lower guide in such position of vertical adjustment as to leave an appropriate spacing 75 between the horizontal members of these co-acting guides between which the edge portion of the cloth travels in a horizontal plane. To prevent the penetration of the extreme edge of the cloth between the two vertical flanges 20^a and 21^a, a portion of the flange 21^a is struck out to form a tongue 21^b adapted to pass through a registering aperture 20^b formed in the flange 20^a and dimensioned to 80 permit the necessary vertical adjustment of 85 the upper guide 21 to accommodate cloth of different thickness.

90 Directly subtending the line of the shears, as shown in Fig. 7, a lateral window or opening, as shown at 22, is provided by omitting 95 at this point the upstanding flanges so as to expose the threads projecting from the edge of the cloth to the action of the shearing couple. In order to direct these threads, which 100 may be right against the bottom or against 105 the top faces of the cloth, outwardly beyond the cloth edge and into the shearing line, I provide upper and lower air blast tubes 23 and 24. It will often be found advantageous 110 to have more than one pair of these air blast tubes arranged at a convenient distance in advance of the aperture or window through 115 which the threads are projected into the shearing line in order to insure moving or blowing the threads outward to the edge of 120 the cloth.

125 It will be found very advantageous to prevent objectionable wrinkling or folding up of the cloth to provide the inner advance corner of the upper guide plate 21 with an upturned integral lip 21^c. I have found that this has a very beneficial effect in preventing trouble due to wrinkling of the cloth when it is under restraint or control of the protective guide.

The fly blade or revolving shear element 13 is driven by means of a pulley 14^a secured to the lower end of the fly blade shaft 14 and driven by a round belt 14^b, which passes over idler pulleys 14^c loosely mounted on a trans-

verse shaft 14^a, whence the belts pass to a suitable driving pulley on the lower part of the machine not herein shown. The idler pulleys 14^c are spaced a sufficient distance to the rear of the pulley 14^a to allow the revolving shear to travel in and out with the carriage, the relatively short distance of the carriage traverse (usually not more than four or five inches), so that the efficiency of the driving belt is not impaired by the relatively slight change of position of the pulley 14^a.

To collect the fly or lint produced by cutting off the threads, I provide a casing 30 around the fly blade 13 and provide this casing with an offtake nozzle 31 adapted to receive a porous bag into which the lint will be blown or be connected with an exhaust pipe through which the air is sucked thereby drawing the fly to a suitable receptacle and at the same time aiding the blast nozzles to project the threads outwardly beyond the edge of the cloth.

In order that the shearing elements and the associated protective guide may promptly follow the swerving movements of the cloth edge, I provide a carriage shifting feeler actuated mechanism, in this case having a feeler finger normally engaging the edge of the cloth and acting to control the movement of the carriage in correspondence with the swerving of the cloth. As shown in Fig. 2 and Fig. 3, double ratchet bars 40, 41 having their ratchet teeth inclined in relatively opposite directions are rapidly reciprocated by means of a pitman rod 42 pivotally attached at its inner end to the bars and at its outer end to an eccentric pin 43 projecting from a pulley 44, which may be driven by a belt or other suitable means to cause rapid vibration of the ratchet bars. Secured to the slidable carriage 5 is a forwardly extending bracket 45 provided with bearing centers for supporting a double ratchet pawl 46 comprising one arm 46^a adapted to engage one of the ratchet bars and be actuated thereby, and another arm or finger 46^b laterally offset to hook into the oppositely inclined ratchet teeth of the other ratchet bar. A light vertical finger 47 projects upward from the pivotal axis of this ratchet pawl or dog in position to engage the overhead edge of the cloth, the protective guide at its angular portion being cut out a short distance, as shown in Fig. 3, to allow the feeler finger 47 complete access to the cloth. The feeler actuated dog is slightly overbalanced on its inner side to normally press the feeler finger lightly against the edge of the cloth travelling through the guide members. Should the cloth swerve inwardly, the inner end of the pawl will engage its ratchet bar on the inward movement thereof, thus shifting the carriage toward the edge of the cloth. On the other hand, should the cloth

swerve outwardly, the pointer to the mem- 70
ber 46^a of the pawl drops into engagement with its actuating ratchet bar and moves the carriage slightly outward. By reason of the lightness of the construction and the direct contact of the feeler with the edge of the cloth and the fineness of the ratchet teeth, the response to any swerving movement of the cloth in either direction is immediate, although the movement on each traverse of the ratchet bar is very slight the vibration of the ratchet bar is so rapid that it suffices to keep the carriage following the cloth edge so long as the swerving in any given direction takes place while quickly causing the carriage to move outwardly as soon as the reverse swerve of the cloth begins.

While in the preferred form of the invention as shown the shearing elements embrace a rotary fly blade and a tangentially arranged ledger blade, which are suitably arranged in relation to a protective guide for the cloth edge, it will be understood that I do not limit myself to that form of shearing couple.

What I claim is:

1. In an edge shearing machine, the combination of a shearing couple embracing thread shearing elements mounted to position their shearing line adjacent the edge of the cloth travelling by, and a protective 95
guide adapted to engage the edge of the cloth and thereby prevent lateral movement of the cloth outside of said shearing line, and means for shifting the shearing elements and the guide in unison to follow the lateral swerving movements of the adjacent cloth edge.

2. In an edge shearing machine, the combination of a shearing couple embracing thread shearing elements mounted to position their shearing line adjacent the edge of the cloth travelling by, and a protective 105
guide adapted to engage the edge of the cloth and thereby prevent lateral movement of the cloth outside of said shearing line, means for shifting the shearing elements and the guide in unison to follow lateral swerving movements of the adjacent cloth edge, and means for projecting the edge threads outward beyond the shearing line 110
to present them to the shearing elements for severance.

3. In an edge shearing machine, the combination with a protective guide arranged to embrace the edge of the cloth and limit the outward swerving of the cloth, of a thread shearing couple associated therewith and embracing a rotary fly blade, and a non-rotating tangentially disposed ledger blade mounted to establish a shearing line close to, and in fixed relation with, the outward limit of movement of the edge of the cloth, said shearing elements and guide being mounted on a carriage movable transversely of the cloth and controlled by the lateral swerving 120

of the cloth to maintain the shearing line in close proximity to the edge of the cloth.

4. In an edge shearing machine, the combination with a protective guide arranged to engage the edge of the cloth and limit its outward movement, of a thread shearing couple embracing a rotary fly blade, and a non-rotative tangentially disposed ledger blade mounted to establish a shearing line opposite a gap in the protective guide in order to shear laterally projecting threads without cutting the cloth, and means for causing the guide and the shearing couple to be moved in and out in correspondence with the in and out swerving movement of the cloth.

5. In an edge shearing machine, the combination with a protective guide arranged to engage the edge of the cloth and limit its outward movement, of a thread shearing couple embracing a rotary fly blade rotatable about a vertical axis, and a tangentially disposed ledger blade, both arranged to establish a shearing line close to the outward limit of movement of the cloth established by said guide, and means for axially reciprocating the shearing couple in relation to the plane of the subtending cloth edge.

6. In an edge shearing machine, the combination with a protective guide arranged to embrace an edge portion of the cloth travelling by and thereby limit the outward movement of the cloth, of air blast pipes arranged to direct blasts of air through the interior of said guide to project the edge threads outwardly through a gap in said guide, shearing means arranged in close proximity to said gap to shear the outwardly projecting threads, and means for shifting the guide and the shearing means in unison in and out to follow the swerving movements of the cloth.

7. In an edge shearing machine, the combination of a transversely movable carriage, a protective guide element mounted on said carriage to embrace the edge of the travelling cloth and limit its outward swerving movement, means for directing blasts of air against that portion of the cloth travelling through said guide to project the edge threads outwardly, shearing elements mounted on said carriage outside said guide close to said guide and in position to sever the threads, thus projected, and means adapted to engage the edge of the cloth and cause an in and out shifting of the carriage thereby moving the shearing elements and the guide in correspondence with the inward and outward swerving movements of the edge of the cloth.

8. In an edge shearing machine, the combination with a carriage movable transversely of the cloth, a protective guide secured to said carriage to embrace the edge of the cloth and limit its outward movement, a vertically reciprocatory carrier mounted in said carriage, shearing elements mounted on said carrier and arranged to establish a vertical

shearing line close to, and outside, the outward limit of movement permitted the cloth by said guide, and means controlled by the cloth to shift said carriage inwardly and outwardly in correspondence with the in and out swerving movements of the cloth.

9. In an edge shearing machine, the combination with a protective guide embracing an edge portion of the cloth and limiting its outward swerving movement, shearing means arranged outside of, and close to, such limit of outward movement to sever threads projecting outwardly from the edge of the cloth, an upright pivotal feeler finger arranged to contact with the edge of the cloth inside the limit of outward movement of the cloth permitted by said guide to permit the finger to move inward and outward in accordance with the in and out movements of the cloth edge, a transversely movable carriage on which are mounted said guide, said shearing means and said feeler finger, and carriage actuating means whose operative connection with the carriage is controlled by said finger.

10. In an edge shearing machine, the combination of a rotary fly blade revolvable about a vertical axis, a tangentially disposed ledger blade, both fly blade and ledger blade being adjustably carried on a common support, a bearing head for rotatably supporting said fly blade, said head being slidably and adjustably secured to said common support to permit adjustment in a vertical plane, a ledger-blade supporting plate adjustably secured to said common support to permit adjustment of the blade in a plane tangential to the fly blade and perpendicular to the plane of adjustment of the fly blade.

11. In an edge shearing machine, the combination of a vertically reciprocatory carrier mounted on a horizontally movable carriage, a rotary fly blade secured to said carrier, a non-rotary ledger blade also secured to said carrier in tangential relation to said fly blade, and means for adjustably setting the respective blades in perpendicular adjusted relationship to each other.

12. In an edge shearing machine, the combination of a reciprocatory carrier, a rotary fly blade secured thereto and rotatable about an axis parallel to said movement of the carrier, a ledger blade disposed in tangential relation to said fly blade, both blades being bodily adjustable in planes perpendicular to each other to secure their proper relative setting for shearing.

13. In an edge shearing machine, the combination with a protective guide embracing the edge of the cloth and limiting its outward movement, one or more blast pipes arranged to deliver compressed air through the interior of said edge embracing guide and outwardly through the edge portion of the guide to the shearing line to expel the edge threads, thread shearing means located close

to, but outside, such limit of movement to sever the projecting threads, and a casing surrounding said shearing means to form an offtake conduit for the air blast to carry away the clipped threads.

5 14. In a shearing machine, the combination with means for guiding the edge of the cloth, thread shearing means arranged in juxtaposition thereto but outside the edge of the cloth, a reciprocatory carrier forming a support for the shearing means to reciprocate the shearing means in parallelism with the shearing line, and a cam for imparting reciprocatory movement to said carrier, said 10 cam being constructed and arranged to maintain operative relation to said carrier in different positions of the carrier transverse to the travel of the cloth.

15 15. In an edge shearing machine, the combination with a protective guide embracing the marginal portion of the cloth and limiting its outward movement, means for supplying a blast of compressed air to the interior of said guide to project threads on the edge of the 20 cloth outward through an opening in said guide, thread shearing means located outside said guide in close relationship to said opening whereby the edge threads of the cloth are expelled through said opening into 25 the shearing line of the shearing means while the adjacent edge of the travelling cloth is maintained out of contact with the shearing 30 means.

In witness whereof I have subscribed the
35 above specification.

CHARLES G. RICHARDSON.
